COATING DEVICE FOR WET PAPER

William M. Nash, Chicago, Ill., assignor, by direct and mesne assignments, of one-fourth to Roy A. Nash, New Rochelle, N. Y., one-fourth to Mary Jones, Neenah, Wis., and one-fourth to Marie Duvall Nash, Neenah, Wis.

Application July 2, 1936, Serial No. 88,551

4 Claims. (Cl. 92—40)

This invention relates to improvements in a device for coating or opacifying paper and refers specifically to improved means whereby a coating or opacifying material may be uniformly and smoothly applied to a continuously travelling web of paper by the use of a dandy roll. It has heretofore been proposed to coat or apply opacifying materials to a continuously travelling paper web by means of a dandy roll. However, difficulty has been encountered in obtaining a smooth, unspotted or unstreaked coating. These difficulties are primarily due to the manner in which the coating or opacifying material is initially applied to the dandy roll prior to its application to the web, the manner of application being such that it was substantially impossible to confine the coating or opacifying material to the surface of the dandy roll. That material which escapes or seeps through the surface 20 of the dandy roll accumulates within the roll and eventually forms a pool at the lower arc of the roll adjacent the point of application of the coating or opacifying material to the web. Here the accumulated material tends to again pass 25 through the meshes of the foraminated surface of the roll and as a consequence irregular deposits of coating or opacifying material have been discharged upon the passing web.

My invention provides means whereby coating material can be conveniently applied to the surface of the dandy roll, the manner of application being such that the coating or opacifying material is substantially entirely confined to the surface of the roll and means is provided whereby 35 that small amount of material which may pass into the interior of the dandy roll is prevented from accumulating adjacent the line of application of the material to the surface of the web. Briefly described, my invention resides in applying coating or opacifying material in the liquid state to a flexible apron or sheet which rests or drags upon the upper foraminated surface of the dandy roll. By applying the coating or opacifying material in this manner the same is transferred to the foraminated surface along a plane tangent to said surface. Hence, by surface tension or capillary phenomenon the coating or opacifying material is carried on the surface of the roll, there being no head or other force 45 tending to cause the material to pass through the meshes or interstices of the foraminated roll surface. Further, the roll is so mounted as to permit a trough to be carried within the interior of the roll to catch or retrieve any coating or opacifying material which may seep through the

meshes of the screen surfaced roll. In this manner, a pool of coating or opacifying material is prevented from accumulating within the dandy roll adjacent the critical point of application of the material to the web.

Other objects and advantages of my invention will be apparent from the accompanying drawings and following detail description.

In the drawings, Fig. 1 is an end elevation of a dandy roll which is provided with the improved means comprising my invention.

Fig. 2 is a top plan view of the device shown in Fig. 1.

Fig. 3 is a sectional view taken on line 3—3 of Fig. 1.

Fig. 4 is a detailed sectional view taken on line 4—4 of Fig. 1.

Fig. 5 is a detailed sectional view taken on line 5—5 of Fig. 1.

Referring in detail to the drawings, 1 indicates a dandy roll assembly, the roll of which is utilized to apply coating or opacifying material to the surface of a newly formed paper web 2 which is carried upon the paper forming screen 3. The assembly 1 may be positioned over the screen 3 at 25 a point along the direction of travel of said screen above the location of the suction boxes (not shown). In the usual Fourdrinier machine the pulp after being discharged or flowed upon the paper forming wire passes over a series of 30 tube rolls wherein a considerable quantity of aqueous carrier of the pulp is removed. After the wire has passed over the last tube roll it travels over a plurality of suction boxes wherein further quantities of the aqueous carrier are removed. It is preferable that the dandy roll assembly 1 be so positioned as to be located approximately midway between the initial and final suction box.

A pair of rails 4 traverses substantially the entire length of the wet end of the Fourdrinier machine and comprises a portion of the paper machine frame. The remaining portion of the frame is not illustrated in the drawings inasmuch as the construction of the usual Fourdrinier paper machine is well known to those skilled in the art. A pair of castings 5 and 6 are mounted upon and secured to opposite rails 4 by means of bolts 7 or the like. The castings 5 and 6 are similar in construction and to the upper portion 45 of each an arcuate shaped arm 8 is secured, said arms being identical in construction. At the free end of each of the arms a bar 9 is pivotally mounted as at 10 in Fig. 1. The bars 9 each comprises a curved section 11 and a curved section 12 55

integrally joined by a straight section 13. The end of the curved section 11 of bar 9 is forked or bifurcated providing a slot 14 between the bifurcations in which a roller 15 is positioned, said 5 roller being carried upon pin 16 which projects through both bifurcations and the end of section 13. The straight section 13 of bar 9 is offset with respect to the curved section 11 and is integrally joined with the lower portion of the 10 curved section 12. The lower end of curved section 12 is also forked or bifurcated and is provided with a slot 17 in which a roller 18 is disposed, said roller being mounted upon pin 19 which projects through both bifurcations and the 15 end of the straight section 13. The upper end of each of the sections 12 of the bars 9 is curved at an angle to the remaining portion of said section and terminates in an arm 20.

Each of the castings 5 and 6 is provided with 20 an opening 21 and 22 respectively through which the arms 20 are positioned, said arms projecting outwardly at their ends from the castings 5 and 6. Lugs 23 and 24 are formed integral with the castings 5 and 6 respectively and project outwardly from said castings. Pins 25 and 26 are mounted upon lugs 23 and 24 respectively and extend upwardly from said lugs. Coil springs 27 and 28 embrace pins 25 and 26 respectively and are confined between lugs 23 and 24 respectively 25 and the outwardly extending ends 20 of sections 12, said ends being provided with apertures through which pins 25 and 26 project. A shaft 29 is journaled adjacent its opposite ends in the castings 5 and 6 and a handle 30 is keyed or 30 otherwise immovably secured to one end of said shaft. A pair of cams 31 are rigidly positioned upon shaft 29, there being a cam 31 within each of the openings or recesses 21 and 22. Cams 31 are eccentrically positioned upon shaft 29 and are disposed immediately beneath each of the 35 extending arms 20. The arrangement is such that, when handle 30 is manipulated, the surfaces of cams 31 are rocked into contact with the lower edges of the arms 20 and, consequently, raise said arms thereby moving bars 9 about the pivot 40 45 points 10 in a counterclockwise direction as viewed in Fig. 1.

A dandy roll 32 is positioned between the opposite castings 5 and 6, said roll being provided 50 with a foraminated or screened surface 33, the meshes of said screen being in the neighborhood of 50 per inch. The ends of the roll 32 comprise rings 34 which are provided with grooves 35. In operation roll 32 is positioned between arms 8 and bars 9 and the ends of said roll are supported by means of rollers 15 and 18, said rollers being adapted to engage rings 34 in grooves 35 as 55 illustrated in Fig. 5. It can readily be seen, therefore, that the dandy roll 32 is not supported from a central axis but is suspended or rests upon rollers 15 and 18, which in turn are carried by bars 9, the ends of which (20) rest upon springs 27 and 28. It can readily be seen, therefore, that the dandy roll 32 is ultimately resiliently 60 mounted or supported upon springs 27 and 28.

Each of the sections 11 and 12 is provided with an aperture 36 and 37 respectively which carry coil springs 38 and 39 respectively. Plugs 40 and 41 respectively are slidably positioned within the 65 apertures 36 and 37 and project outwardly from the surfaces of sections 11 and 12. The outer ends of plugs 40 and 41 are adapted to project into the grooves 35. In view of the fact that rollers 15 and 18 are positioned within grooves 35 adjacent the lower portion of the rings 34, and plugs 70 75

40 and 41 are positioned within said grooves at a higher portion of said rings, axial movement of the roll 32 is effectively prevented. Plugs 40 and 41 are preferably constructed of wood saturated with oil or may be constructed of any so-called self-lubricating material. 5

Upright members 42 carrying outwardly extending lugs 43 at each of their lower ends, are mounted upon the opposite sections 13 of bars 9, said upright members being spaced from each other as shown in Fig. 1. Each of the lugs 32 is apertured and bolts 44 function to secure said lugs to the sections 13. The positioning of the upright members 44 is such that said members pass axially through the interior of roll 32. A trough 45 is secured at each of its longitudinal edges to the upright members 42 whereby a tray is provided within roll 32 which traverses the length of said roll. A pipe 46 is also positioned axially within the interior of roll 32, said pipe being provided with a plurality of apertures 47 which open toward the interior surface of the foraminated roll 32. Pipe 46 is adapted to carry steam under pressure which is discharged through the apertures 47, the jets of steam issuing from said apertures being directed against the screen 33 whereby the same may be cleansed. 10 15 20 25 30 35 40 45 50 55 60 65 70 75 80 85 90 95 100

A supporting member 48 may be secured to the web by means of bolts or the like 49 of each of the arms 8, said supporting members projecting upwardly and each terminating in a U-shaped saddle 50. A bar 51 is adapted to rest at each of its ends within the saddles 50, said bar being disposed parallel to the axis of the roll 32. A flexible apron 52 is secured adjacent one of its side edges to bar 51. The apron 52 may be constructed of rubber, rubberized cloth, felt or other flexible material. The free end of the apron 52 is adapted to rest upon or drag upon the rotating surface of the roll 32 as indicated at 53 in Fig. 1. 40 45 50 55 60 65 70 75 80 85 90 95 100 A socket or saddle 54 may be integrally formed upon each of the webs of arms 8, said sockets or saddles being adapted to carry a pipe 55 which transversely spans the assembly. Pipe 55 is provided with a plurality of nozzles 56 which discharge toward the flexible apron 52. As will be hereinafter more fully described, pipe 55 is adapted to carry coating or opacifying material under pressure, which material is discharged into contact with apron 52 and ultimately deposited upon the foraminated surface of roll 32.

In operation, a newly formed relatively wet web 2 is carried upon the Fourdrinier wire 3 beneath the dandy roll assembly 1. With roll 32 in operative position, arms 20 rest upon coil springs 27 and 28 and the foraminated surface 33 of roll 32 exerts a slight pressure upon web 2 which passes therebeneath. Coating or opacifying material, comprising the usual coating substances in liquid suspension or solution, is passed through pipe 55 under superatmospheric pressure and is sprayed from nozzles 56 into contact with the concave surface of the flexible apron 53. 55 60 65 70 75 80 85 90 95 100

The free end of apron 53 rests upon or drags upon the upper surface of the roll 32 as the same is rotated by contact with the web 2 and the length of the apron is such with respect to the relative position of the rod 51 and roll 32 as to have its lower edge terminate adjacent the top of roll 32. The length of the apron is also such that the end or lower edge thereof is disposed substantially tangentially to the roll 32. It can readily be seen, therefore, that the liquid material discharged to the surface of the apron flows downwardly along the concave side of the apron 70 75 80 85 90 95 100

and flows substantially tangentially onto the screen surface 33. Hence, there is substantially no force, such as an appreciable liquid head or pressure head which would tend to cause said 5 coating or opacifying material to pass through the meshes or interstices of the foraminated surface. The mesh of the foraminated surface is, of course, sufficiently small to permit the retention, by surface tension, of the liquid upon the 10 surface.

Of course, it is substantially impossible to entirely prevent the material from passing into the interior of the roll and, hence, the trough 45 is provided within the roll adjacent the descending 15 side thereof. The trough 45 is adapted to retrieve or catch the seepage through the surface of the roll and thereby prevent an accumulation of coating or opacifying material within the roll adjacent its line of contact with the web. Of course, the trough 45 can be conveniently disposed within the roll because of the suspended 20 mounting of the roll whereby no interfering spokes or radial arms are necessary.

I claim as my invention:

25 1. In combination with a paper making machine wherein a relatively wet newly formed web is continuously carried forwardly upon a paper forming wire, means for coating a surface of said web comprising, a dandy roll supported above the 30 path of travel of the web, the surface of said roll being in contact with said web, means for discharging coating material onto the surface of said roll whereby the same is deposited by said roll upon the surface of the web, said means comprising a flexible apron positioned above said 35 roll, said apron contacting the roll along a substantially tangential plane adjacent the top of the roll, and means for distributing a mobile coating material upon said apron, and a trough 40 disposed within the roll and coextensive with the length thereof for retrieving coating material which passes through the surface of the roll.

2. In combination with a paper making machine wherein a relatively wet newly formed web is continuously carried forwardly upon a paper 45 forming wire, means for coating a surface of said web comprising, a dandy roll supported above the path of travel of the web, the surface of said roll being in contact with said web, means for dis-

charging coating material onto the surface of said roll whereby the same is deposited by said roll upon the surface of the web, said means comprising a flexible apron positioned above said roll, said apron contacting the roll along a substantially tangential plane adjacent the top of the roll, and means for distributing a mobile coating material upon said apron, and a trough disposed within the roll for retrieving coating material which passes through the surface of the roll. 10

3. In combination with a paper making machine wherein a relatively wet newly formed web is continuously carried forwardly upon a paper forming wire, means for coating a surface of said web comprising a roll having a foraminated surface positioned above the path of travel of the web, means for resiliently supporting said roll, the surface of said roll being in resilient contact with said web, and means for flowing coating material by gravity substantially tangentially on 15 to the surface of said roll whereby the same is deposited by said roll upon the surface of the web, said means comprising a flexible apron supported above said roll, the opposite edge of which drags upon the surface of said roll along a substantially tangential plane, a trough disposed within the roll for retrieving coating material which passes through the surface of the roll, and spray means within said roll for discharging fluid into 20 contact with said foraminated surface to clean 30 the same.

4. In combination with a paper making machine wherein a relatively wet newly formed web is continuously carried forwardly upon a paper forming wire, a frame positioned over the path 35 of travel of said web, a dandy roll supported on said frame, the surface of said roll being in contact with said web, means for discharging coating material onto the surface of said roll, a trough disposed within the roll for retrieving coating material which passes through the surface of said roll, a dandy roll support comprising a pair of spaced arms each of which is pivotally mounted at one end upon said frame, rollers carried by said arms upon which the lower portion of the periphery of the dandy roll rests, and resilient means for supporting the opposite ends of said roller carrying arms. 30

WILLIAM M. NASH.
